His Attorney.

UNITED STATES PATENT OFFICE

2,471,848

COMBINED SWITCH AND FUSE

Fred G. von Hoorn, Bridgeport, Conn., assignor to
 General Electric Company, a corporation of
 New York

Application December 29, 1945, Serial No. 638,060

8 Claims. (Cl. 200—114)

1

My invention relates to a circuit controlling device and more particularly to a fuse structure provided with a built-in switch mechanism for temporarily closing the fuse circuit in the event that the fuse blows. In one form, my invention is employed in connection with an indicating fuse arrangement.

It is an object of my invention to provide a new and improved circuit controlling device which comprises a combined fuse and switch structure in which the switch mechanism has built into it a receptacle for receiving a fuse. The arrangement is such that on overloads the fuse blows to protect the line, but in the event that the line must be cleared temporarily in an emergency, the switch mechanism may be operated to accomplish this.

It is a further object of my invention to provide a circuit controlling device consisting of a combined fuse and switch mechanism which is formed of relatively few parts designed to give a compact arrangement particularly suited for mounting on a panel.

Still another object of my invention is the provision of a circuit controlling device including a fuse and switch in combination with an indicating lamp, the arrangement being such that the lamp lights when the fuse blows and goes out when the switch is operated.

In the accompanying drawing, Fig. 1 is a perspective view of a circuit controlling mechanism constructed in accordance with my invention; Fig. 2 is a view of the interior of the mechanism with the cover removed; Fig. 3 is a sectional view through the combined fuse and switch structure, and Fig. 4 is a diagram of the electrical circuit through the device.

Referring to the drawing, my circuit controlling device is provided with a housing 1 formed of a supporting plate 2 and a cover 3. A portion of plate 2 is bent at an angle to form a mounting panel 4. The panel carries oppositely extending ears 5 for mounting the device on a support by screws which extend through the support into threaded receptacles 6. The cover 3 is held in position by a screw 7 extending into a bracket 8 formed in the front panel 5. The circuit controlling device includes a combined fuse and switch mechanism 9 extending through the front panel 5 to a position such that it is easily accessible for operation. The switch is operated simply by pushing in on the member 9. The fuse operates in the circuit in the usual way. The condition of the fuse is indicated by an indicating light 10 carried by the front panel 5.

2

When the fuse blows, the light 10 comes on to indicate that the fuse should be replaced. The electrical circuit through the circuit controller is illustrated in Fig. 4.

Referring to Fig. 4, the circuit controlling device is placed across the two conductors 11 and 12 of a power supply line which is to be protected. Protection of the circuit is afforded by a fuse 13. In normal operation current flows from line 11 through a conductor 14, fuse 13, conductor 15 back to the other side 12 of the power supply. When the fuse blows due to a fault in the line, the power supply circuit is interrupted. Current now flows from line 11 through a voltage reducing resistor 16 to the lamp 10 and then back to the other supply line 12. In certain situations, as in an emergency, it is desirable to provide means whereby the circuit through the power supply lines 11 and 12 may be reestablished for a short time interval, even though the fuse 13 has blown indicating that a fault exists in the circuit. To accomplish this result, I provide a switch means 17 associated with the fuse and comprising normally spaced contact members. In order to close the switch, the combined fuse and switch mechanism 9, including the fuse 13, is moved to the right, in the showing of Fig. 4, to close a circuit through the switch contacts. In this way, the circuit across supply lines 11 and 12 may be manually closed for any desired length of time for use during emergency operation. The arrangement is particularly useful in protective circuits on aircraft.

Turning now to the structure of my circuit controlling device and referring to Fig. 3, I provide a casing 18 of insulating material which is formed as an elongated cylinder having a recess 19 for receiving the fuse 13. By way of example, I have illustrated the fuse 13 as being of the cartridge type although it should be manifest that other types of fuses may be used equally as well. In order to support the fuse 13 and for making an electrical connection therewith, the casing is provided with a clip 20 at the bottom of the recess 19, the clip being formed as a cylindrical cup-shaped member for receiving one of the ferrules on the fuse 13. The casing is also provided with a cylinder 21 set in the recess 19 and which is formed of a thin metallic conducting sleeve. It is screw threaded at one end, as shown at 22. A plug 23 of insulating material is provided to close the end of the recess 19. To this end, the plug is provided with an extension 24 provided with screw threads for engaging the threads 22 on the cylinder 21 so that the

plug may be mounted in position on the casing. The end of the plug is provided with a clip 25 formed as a cup-shaped member and which is adapted to receive the other ferrule of the cartridge fuse 13. The clip 25 is fastened to the end of the plug by means of a drive pin 26.

When it is desired to insert a cartridge fuse in the casing, the plug 23 is removed and one ferrule of the fuse inserted in the clip 25. Then the assembled fuse and plug are inserted in the casing so that the other ferrule of the fuse is seated in position in the clip 20. By threading the plug 23 down into seated position in the casing, the fuse cartridge is forced into seated position against a coiled spring 27 so that a good electrical connection is provided between the clips and the fuse ferrules. The clip 25 in the plug is wedged in between the wall of cylinder 21 and the fuse ferrule so that a good electrical connection is obtained between the fuse ferrule and the cylinder 21. The structure provides a means for easy replacement of the fuse. Electrical connections are made with opposite ends of the fuse in the following way.

Referring to Fig. 2, it will be seen that the conductor 14 is electrically connected to a terminal 28 extending outwardly from the casing 18. This terminal extends through the wall of the casing into engagement with the conducting cylinder 21 so that an electrical connection is provided between the conductor 14 and the clip 25 which engages one of the fuse ferrules. The other conductor 15 is electrically connected to a U-shaped spring support 29 which is fastened to the end of the casing as by a rivet 30 or other suitable fastening means. The rivet 30 extends through the wall of the casing and makes electrical contact with the interior fuse clip 20 so that an electrical connection is provided between the conductor 15 and the other ferrule of the fuse. The structure thus far described gives fuse protection to the associated power supply circuit. In the event that the fuse blows, additional switch mechanism is provided so that the power supply circuit can be closed in an emergency.

The switch mechanism is built into and forms part of the fuse structure. It includes two normally spaced contact buttons 31 and 32. The contact button 31 is fastened to the spring support 29 so that it is electrically connected to both the conductor 15 and one end of the fuse. The other contact button 32 is supported on a plate of insulating material 33 which is fastened to upstanding ears 34 on the plate 2. A terminal lug 35 is connected to contact 32 for making an electrical connection with the conductor 11 of the supply line. In order to operate the switch mechanism, the casing 18 containing the fuse is moved back and forth to open and close the circuit through the contacts 31 and 32 in a manner now to be described.

The casing 18 is slidably mounted on the supporting plate 2. To this end, the end of the casing opposite the contact 31 is formed with an enlarged head portion 36 which extends through an opening 37 in the front panel 5. In order to limit outward movement of the casing a washer 38 is slipped over the narrower portion of the casing and rests against the head 36. It is held in position by a nut 39 threaded onto the screw threads 40 formed about a portion of the outer circumference of the casing 18. A collar 41 of insulating material is then slipped into position over the threads and is held by a sleeve 42 which surrounds the casing and which forms an abut-

ment for a biasing spring 43. The spring 43 is coiled around the outside of the casing and is compressed between the sleeve 42 and a bracket 44 carried by the supporting plate 2. As shown in Fig. 2, the sleeve 42 is provided with a slot 45 which extends around terminal 28 so that the sleeve 42 may be slipped over the casing around the terminal to the position shown.

During manufacture, the washer 38 and nut 39 are first located in position on the casing and then the collar 41 and the sleeve 42 are assembled in position. The casing 18 is then inserted through the opening 37 in the front panel 5 so that the washer 38 rests against the inner face of the panel. Spring 43 is then slipped over the casing and the bracket 44 mounted in position to support the other end of the casing. Once the parts are assembled in position, the bracket 44 is fastened to the plate 2 in any suitable manner, as by rivets 46. After final assembly, the contact button 31 is normally spaced from the contact 32 and is held in this position by the biasing action of the compression spring 43. When it is desired to operate the switch mechanism, the head 36 is simply pressed inwardly against the spring action to close the contacts. It may be held in this position as long as desired.

I prefer to use my circuit controlling device in conjunction with an indicating lamp which will show when the fuse 13 has blown. The lamp 10 is a standard type indicating light now available on the market. It is electrically connected to the power supply 12 and to the resistor 16 in the manner shown by Fig. 4. The resistor 16 is mounted on the insulating plate 33 by means of a lock washer 47 and screw 48. In addition to giving an indication when the fuse is blown, the indicating light serves to show the operator that the circuit is closed when the switch mechanism is operated. Upon operation of the switch, the circuit to the lamp will be short circuited and the light will go out.

The fuse and switch structures are combined into a single mechanism which provides a compact arrangement of the parts taking up little space. The device is particularly well suited for panel mounting. When in mounted position, the operating head 36 extends beyond the panel where it is readily accessible for operation of the switch mechanism. Moreover, the fuse is easily accessible for replacement. The fuse itself is removed from the casing by removing the plug 23 inasmuch as the fuse is frictionally held in the clip 25 carried by the plug; the spring 27 acts to remove the fuse from engagement with the inner clip 20.

What I claim as new and desire to secure by Letters Patent of the United States is:

1. A circuit controlling device comprising, in combination, a supporting member, a casing of insulating material carried by said supporting member for sliding movement thereon, said casing being provided with a recess having spaced contact clips therein, a cartridge type fuse in said recess carried by said contact clips, cooperating contact means carried by said casing and said support respectively, one of said contact means being electrically connected to one of said contact clips, said contact means being operated to closed circuit position upon sliding movement of said casing and spring means biasing the contact means to open circuit position.

2. A circuit controlling device comprising, in combination, an elongated casing of insulating material having a recess therein, spaced contact

clips in said recess, a cartridge type fuse in said recess making an electrical connection with said contact clips, spaced supports, said casing being mounted on said supports for sliding movement therein, an electrical contact carried by said casing and being electrically connected to one of said contact clips, a fixed contact carried by one of said supports, said casing being movable to engage said mentioned contacts for closing an electrical circuit therethrough.

3. A circuit controlling device comprising, in combination, an elongated casing of insulating material having a recess therein, spaced contact clips in said recess, a cartridge fuse in said casing making an electrical connection with said contact clips, supporting means for slidably mounting said casing, and switch means electrically connected to one of said contact clips and being operable upon movement of said casing for controlling a circuit.

4. A circuit controlling device comprising, in combination, a supporting member, a casing of insulating material carried by said supporting member for sliding movement thereon, said casing being provided with a recess having spaced contact clips therein, a cartridge-type fuse in said recess carried by said contact clips, an electrical contact carried by said casing and being electrically connected to one of said clips, a fixed contact carried by said support and adapted to be engaged by the movable contact upon movement of said casing, and spring means carried by said casing for biasing said contacts to open circuit position.

5. A circuit controlling device comprising, in combination, a supporting member, a casing of insulating material carried by said supporting member for sliding movement thereon, a cartridge type fuse carried by said casing, cooperative contact means carried by said casing and said support and being electrically connected to said fuse, movement of said casing in one direction closing the circuit through said contact means, and spring means carried by said casing for maintaining the contact means in open circuit position.

5 6. A circuit controlling device comprising, in combination, a supporting member, a casing of insulating material carried by said supporting member for sliding movement thereon, said casing being provided with a recess having spaced contact clips therein, a cartridge type fuse in said recess carried by said contact clips, a plug for closing said recess, an electrical contact carried by said casing electrically connected to one of said clips, a fixed contact carried by said support and adapted to be engaged by the movable contact upon sliding movement of said casing, and spring means disposed around said casing for biasing said contacts to open circuit position.

10 15 7. A circuit controlling device comprising, in combination, a casing slidably mounted for movement on a support, a fuse carried by said casing for protecting an electric circuit, and switch means operated by manual movement of said casing to close the circuit in the event that the fuse blows.

20 25 8. A circuit controlling device comprising, in combination, a supporting member, a casing of insulating material carried by said supporting member for sliding movement thereon, an electrical fuse carried by said casing, an electrical contact carried by said casing and being electrically connected to one end of the fuse, a fixed contact carried by said support and adapted to be engaged by the movable contact upon movement of said casing, and spring means carried by said casing for biasing said contacts to open circuit position.
